UNITED STATES PATENT OFFICE

157,263

BELT BUCKLE

John S. Justin, Jr., Fort Worth, Tex.

Application September 26, 1949, Serial No. 5,174

Term of patent 14 years

(Cl. D17—1)

To all whom it may concern:

Be it known that I, John S. Justin, Jr., a citizen of the United States, residing at Fort Worth, in the county of Tarrant and State of Texas, have invented a new, original, and ornamental Design for a Belt Buckle, of which the following is a specification, reference being had to the accompanying drawing, forming part thereof.

Figure 1 is a front elevation of a belt buckle showing my new design. Figures 2 and 3 are, respectively, perspective and end views showing the back and one end of the buckle illustrated in Figure 1, but on a greatly reduced scale in comparison with the disclosure in Figure 1.

I claim:

The ornamental design for a belt buckle, as shown.

JOHN S. JUSTIN, JR.
